TELEVISION RECEIVER

William A. Tolson, Westmont, N. J., assignor to
Radio Corporation of America, a corporation
of Delaware

Application July 31, 1941, Serial No. 404,786

11 Claims. (Cl. 250—36)

My invention relates to television apparatus or the like and particularly to television receiver deflecting circuits.

In television systems employing interlaced scanning, it has been found that considerable difficulty may be encountered in making the scanning pattern interlace properly. One of the reasons for this difficulty is that after the oscillator in the vertical deflecting circuit has been triggered off by an incoming synchronizing pulse, there may be a change in the latter portion of the pulse (due to noise, for example) which will affect the oscillator output.

An object of the present invention is to provide an improved method of and means for synchronizing a cathode ray deflecting circuit.

A further object of the invention is to provide an improved deflecting circuit for use in a television receiver employing interlaced scanning.

A still further object of the invention is to provide an improved deflecting circuit which is little affected by undesired variations in the synchronizing signal.

In a preferred embodiment of the invention, the vertical deflecting circuit of a television receiver contains a blocking oscillator which is synchronized by vertical synchronizing pulses applied through an amplifier tube. The coupling circuit between the amplifier tube and the oscillator is such that the oscillator pulse, which occurs as soon as the oscillator is triggered off by the first occurring portion of a synchronizing pulse, drives the plate of the amplifier tube negative and holds it negative during the remainder of the synchronizing pulse. Thus, any variations in the latter portion of the synchronizing pulse cannot affect the oscillator output.

The invention will be better understood from the following description taken in connection with the accompanying drawings in which

Figure 1 is a circuit and block diagram of a television receiver which includes one embodiment of my invention,

Figures 2a and 2b are curves which are referred to in explaining the invention, and

Figures 3, 4 and 5 are circuit diagrams of other embodiments of the invention.

In the several figures corresponding parts are indicated by like reference characters.

Referring to Fig. 1, the invention is shown applied to a television receiver which is to operate in a system employing odd-line interlacing, the synchronizing signal being the standard signal illustrated in Bedford Patent 2,223,812 issued December 3, 1940. The receiver is of the usual su-

perheterodyne type having a first detector and tunable oscillator indicated at 10, an I. F. amplifier 11, a second detector 12, a video amplifier 13, and a cathode ray receiver tube 14. The tube 14 is provided with horizontal deflecting coils 16 and vertical deflecting coils 17.

Signal from the second detector is supplied over a conductor 18 and through an amplifier 19 to a separating tube 21. In the particular circuit illustrated, the separating tube 21 is of the grid leak biased type, only the horizontal and vertical synchronizing pulses, which are positive at the grid of the tube 21, appearing in its plate circuit.

The horizontal or line frequency synchronizing pulses, after being amplified and separated from the vertical synchronizing pulses in a circuit indicated at 22, are applied to the horizontal deflecting circuit indicated at 23.

The vertical synchronizing or framing pulses are separated from the horizontal synchronizing pulses by a suitable filtering or integrating circuit as is well known in the art. In the particular circuit shown, the input circuit of an amplifier tube 24 includes an integrating circuit which comprises a series resistor 26 and a shunt condenser 27 connected between the grid of tube 24 and ground. A small positive bias is applied to the grid of the tube 24 through a resistor 28 and the resistor 26. This specific integrating circuit is described and claimed in Patent 2,219,579 issued October 29, 1940 to W. J. Poch.

The resistor 29 and condenser 31 are the usual plate resistor and coupling condenser, respectively.

The vertical synchronizing pulse at the grid of the amplifier tube 24 has a wave shape substantially as shown by the curve 32 in Fig. 2a. This pulse is amplified by the tube 24 and applied to a blocking oscillator 33 which is adjusted in the usual manner to have a free-running frequency slightly lower than the synchronous frequency.

The blocking oscillator 33 comprises a vacuum tube 34 and the usual iron-core feedback transformer 36, grid condenser 37 and grid leak resistor 38. The oscillator pulses are applied to a suitable saw-tooth wave generating circuit which, in this example, comprises a discharge tube 39 through which a condenser 41 is discharged rapidly after being charged comparatively slowly through a plate resistor 42. The conventional "peaking" resistor 43 may be employed so that the output tube 44 will produce deflecting current in the coils 17 which has a straight saw-

tooth wave form.

In accordance with my invention the connection between the amplifier tube 24 and the oscillator 33 is such that the voltage "back-kick" from the oscillator drives the plate of tube 24 negative with respect to ground to make the amplifier momentarily nonconducting. Referring to this connection, an operating voltage is applied to the plate of tube 24 through a filter resistor 46 and a plate resistor 47. The condenser 48 is the usual filter condenser.

The plate of tube 24 is connected to one end of the secondary of the feed-back transformer 36, and through this secondary and the grid condenser 37 to the grid of the oscillator tube 34.

A condenser 51 is connected between the plate of tube 24 and ground, this condenser having the effect of widening the oscillator pulse to produce the pulse 52 (Fig. 2b) which appears on said plate. The capacity of condenser 51 is sufficient to widen the pulse 52 enough so that the plate of tube 24 is held negative until substantially the end of the synchronizing pulse 32 or longer. This action of the circuit in disconnecting or rendering nonconducting the tube 24 is illustrated in Fig. 2b. It is apparent that the negative pulse 52 produced by the oscillator makes the tube 24 ineffective to transfer signal as soon as the synchronizing pulse 32 rises to a voltage high enough to trigger off the oscillator, and that the pulse 52 holds the tube 24 in this condition long enough to prevent the remainder of the synchronizing pulse 32 from affecting the oscillator.

It will be understood that the values of circuit elements and of tube voltages are not critical. However, they must be such that for a substantial period the oscillator voltage 52 is greater than the plate operating voltage of tube 24. In the circuit of Fig. 1 less than normal operating voltage is applied to the plate of the tube 24 whereby less oscillator voltage is required at the amplifier plate to hold it negative for the required time.

Figs. 3, 4 and 5 show other circuits for connecting the amplifier 24 to the oscillator to obtain the above-described operation.

In Fig. 3 the plate of tube 24 is connected to the rated plate voltage through a plate resistor 53 of unusually high resistance. As in Fig. 1, there is a condenser, indicated at 54, connected between the amplifier plate and ground. The oscillator grid condenser 56 has a fairly small capacity whereby a very steep front for the oscillator pulse 52 is assured. The relative values of elements 53 and 54 are such that they widen the oscillator pulse a sufficient amount to hold tube 24 nonconducting for the required time as explained in connection with Fig. 1. It may be noted that this widening of the oscillator pulse is by an integrating action.

In Fig. 4 the connection between the amplifier 24 and the oscillator 33 is such that the sawtooth voltage which appears across the oscillator condenser 57 is impressed upon the amplifier plate through a coupling condenser 58, the plate resistor 59 of the amplifier having high resistance. This sawtooth voltage corresponds to the pulse 52 (Fig. 2b) and performs the same function. The oscillator grid leak resistor 61 is connected from the junction point of the condenser 58 and the transformer secondary to ground.

In Fig. 5, also, the oscillator voltage across the grid circuit condenser 57 is utilized to drive the plate of tube 24 negative. Here the grid leak resistor 61, instead of being connected directly to

ground, is connected to ground through the plate resistor 59 and the amplifier plate voltage supply.

In the several figures the values of various circuit elements have been indicated, merely by way of example, in ohms, megohms, microfarads, and micromicrofarads.

I claim as my invention:

1. In combination, an oscillator which is to be synchronized by synchronizing pulses, said oscillator being of the type which produces periodic voltage pulses of high amplitude, an amplifier tube through which said synchronizing pulses are applied to said oscillator, said tube having a cathode and a plate, and means for coupling the plate of said amplifier to a point in said oscillator where negative oscillator pulses occur with sufficient amplitude to drive said plate negative with respect to said cathode immediately following the occurrence of a synchronizing pulse and to hold it negative at least for substantially the duration of the synchronizing pulse.

2. The invention according to claim 1 wherein said coupling means includes means for increasing the width of the oscillator pulses.

3. The invention according to claim 1 wherein there is a condenser connected between the plate of said amplifier and ground for widening the oscillator pulses.

4. In combination, a blocking oscillator which is to be synchronized by synchronizing pulses, an amplifier tube through which said pulses are applied to said oscillator, said tube having a plate, and means for coupling the plate of said amplifier to a point in said oscillator where negative oscillator pulses occur with sufficient amplitude to drive said plate negative with respect to the cathode immediately following the occurrence of a synchronizing pulse and to hold it negative at least for substantially the duration of the synchronizing pulse.

5. The invention according to claim 4 wherein said coupling means includes means for increasing the width of the oscillator pulses.

6. The invention according to claim 4 wherein there is a condenser connected between the plate of said amplifier and ground for widening the oscillator pulses.

7. In combination, a blocking oscillator which is to be synchronized by a signal comprising periodic pulses, an amplifier tube through which said signal is applied to said oscillator, said tube having a plate and a cathode, and means for coupling the plate of said amplifier to a point in said oscillator where there is produced in response to the application of a synchronizing pulse an oscillator pulse which drives said plate to a potential which does not substantially exceed the potential of said cathode and which holds it negative at least for substantially the duration of the synchronizing pulse.

8. The invention according to claim 7 wherein said coupling means includes means for increasing the width of the oscillator pulses.

9. The invention according to claim 7 wherein there is a condenser connected between the plate of said amplifier and ground for widening the oscillator pulses.

10. In combination, a blocking oscillator adapted to have its rate of oscillation controlled by the application thereto of a frequency controlling signal, means for producing a frequency controlling signal in which there are periodically recurring pulses that recur at a rate having a definite frequency relation to said rate of oscillation.

lation, said oscillator comprising a vacuum tube having a control grid and a plate, said oscillator further comprising a transformer having a primary coil in the plate circuit of said tube and having a secondary coil in the grid circuit of said tube, one end of the secondary coil having a connection to said control grid, an amplifier tube through which said controlling signal is applied to said oscillator, said amplifier tube having a plate, and means for coupling the plate of said amplifier to a point in said oscillator where negative oscillator pulses occur with sufficient amplitude to drive the plate of said amplifier tube negative immediately following the occurrence of each of said pulses in the controlled signal and to hold it negative at least for substantially the duration of the pulses in the controlling signal, said coupling means including a connection from the plate of said amplifier to the other end of said secondary coil.

11. In combination, a blocking oscillator which is to be synchronized by synchronizing pulses,

said oscillator comprising a vacuum tube having a control grid and a plate, said oscillator further comprising a transformer having a primary coil in the plate circuit of said tube and having a secondary coil in the grid circuit of said tube, one end of the secondary coil having a connection to said control grid, an amplifier tube through which said synchronizing pulses are applied to said oscillator, said amplifier tube having a plate, and means for coupling the plate of said amplifier to a point in said oscillator where negative oscillator pulses occur with sufficient amplitude to drive the plate of said amplifier tube negative immediately following the occurrence of a synchronizing pulse and to hold it negative at least for substantially the duration of the synchronizing pulse, said coupling means including a connection from the plate of said amplifier tube to the other end of said secondary coil.

WILLIAM A. TOLSON.
